ELECTRON DISCHARGE TUBE

Howard James Louis Herne, London, England, assignor to The Hartford National Bank and Trust Company, Hartford, Conn., as trustee

Application August 30, 1944, Serial No. 551,883
In Great Britain May 10, 1943

7 Claims. (Cl. 250—27.5)

This invention relates to electron discharge tubes and has for its object to provide a convenient electrode assembly whereby two adjacent electrodes are secured in predetermined relationship under operating conditions.

According to the present invention the said two electrodes are carried by common supports sealed in the envelope, one electrode being directly carried by the supports which also constitute the electrical connection to this electrode and the other being indirectly carried by way of insulating beads of glass or other thermoplastic material which does not soften under the conditions obtaining during normal operation of the tube, the electrical connection to this other electrode being effected by a separate lead-in wire.

In a preferred construction according to the present invention two support wires sealed in the envelope are welded or otherwise secured to one electrode and are stepped outwardly away from the electrode system and extend beyond the active face of the said one electrode, the ends of the wires being sealed in insulating beads in each of which is also sealed one end of a wire the other end of which is secured to the second electrode, the insulating beads forming an insulating mechanical connection between the two sets of wires.

The present invention is applicable with particular advantage to electron discharge tubes in which two adjacent electrodes are substantially in contact, one of the electrodes being coated with an insulating coating preferably in the form of an emissive oxide coating. In the case of a contact diode, both cathode and anode are conveniently constructed as cup or pot shaped electrodes and are mounted with their closed ends in contact, the cathode being mounted directly on the support wires. The lead-in wire to the anode is preferably flexible, for instance in the form of a strip or ribbon attached at one end to the anode and at the other end to a lead-in conductor sealed in the envelope, the strip or ribbon comprising a zig-zag or corrugated portion intermediate its ends.

The wires extending between the glass beads and the two electrodes are chosen of such coefficient of expansion and the points of attachment of the wires to the electrodes are so selected, that at the working temperatures of the components of the tube, the two electrodes are at the desired spacing.

Reference will now be had to the accompanying drawing, which shows one embodiment of the invention by way of example and in which

Fig. 1 is a longitudinal section through the electron discharge tube, prior to the sealing off of the envelope.

Fig. 2 is a cross section substantially along the line 11—11 of Fig. 1.

Fig. 3 is a cross-sectional view of the anode lead-in conductor.

The discharge tube shown is a diode, the cathode 8 and the anode 16 each consisting of a pot or cup-shaped electrode, the closed ends being adjacent each other.

Sealed in one end of the glass envelope 1 are support and lead-in wires 2, 3 for the cathode as well as a further lead-in wire 4 for the cathode heater 9, the circuit of which is completed by way of the cathode support 3. The upper ends of the wires, 2, 3, 4, are located by a mica disc 5 which has apertures for the passage of the wires and which is supported by metal collars 6, 7, on the support wires 2, 3. The pot cathode 8 is welded to two metal wires 10, 11, the lower ends of which are attached to the upper ends of the wires 2, 3. The upper parts of the wires 10, 11 are stepped outwardly away from the cathode 8 and are embedded in glass beads 12, 13. Also embedded in the glass beads 12, 13 and insulated by the glass from the rods 10, 11 are metal wires 14, 15 of substantially J or U shape. The free ends of these wires 14, 15 are welded to the pot anode 16 so as to support the latter, with its closed end adjacent the closed end of the cathode 8.

Secured to the wires 14, 15 is a metal cross wire 17 to which the anode lead-in conductor is attached. This conductor consists of a wire 19 and a flexible metal strip 18 which preferably has a zig-zag or corrugated portion as shown in Fig. 3. The anode lead-in conductor is located within the envelope by a mica disc 20 held between two metal collars 21, 22 on the wire 19.

For facilitating the sealing-off, the wire 19 is provided with a glass bead 23 which after the discharge tube has been degassed is fused to the glass of the envelope.

With an indirectly heated cathode 8 as shown, the surface adjacent the anode 16 will be coated in the usual way with an emissive oxide coating. The anode 16 and cathode 8 may be at a perceptible separation as shown, or they may be substantially in contact but insulated from each other by the oxide coating.

For obtaining contact between the two electrodes 8, 16 or only a very slight separation, it is preferred to proceed as follows: the electrode assembly 2—23 is first made with the surfaces of the electrodes 8, 16 in contact. The assembly is

then introduced into the envelope 1 through the lower end, and the seal is produced about the support wires 2, 3 and the heater lead 4 which are to pass through this end of the tube. The tube is then connected with the pumps and degassing is effected. While still on the pumps, the cathode 8 is heated to such an extent that the glass beads 14, 15 soften adjacent the end of the wires 10, 11. The heating may be effected by the cathode heating coil 9, by eddy current heating, or by the two in combination. In any case, the wires 10, 11 are heated chiefly by conduction from the cathode 8. When the glass beads 12, 13 soften, the anode 16 simply rests on the cathode 8. On cooling, the glass of the beads 12, 13 first hardens, and then in accordance with the different coefficients of expansion and the different expanding lengths, the surfaces of the electrodes are caused to assume a predetermined spacing at the working temperature of the tube; the spacing may be perceptible or may be vanishingly small. After this heating stage and after completed degassing, the tube is sealed off by fusing the bead 23 to the neck of the tube. The mica disc 20 secured on the lead-in conductor 19 prevents any undesired outward movement of the latter relatively to the tube during the sealing-off operation.

Although the drawing shows the invention as applied to a diode, it will be apparent that the invention can be applied to an electron discharge tube with more than two electrodes, by providing a sequence of alternate insulating beads 12, 13 and supporting wires 14, 15, all carried by the primary supports 2, 3 which are sealed into the envelope.

I claim:

1. An electron discharge tube wherein two adjacent electrodes are carried by common supports sealed in the envelope, one electrode being directly carried by the supports which also constitute the electrical connection to this electrode, and the other being indirectly carried by way of insulating beads of thermoplastic material which does not soften under the conditions obtaining during normal operation of the tube, the electrical connection to this other electrode being effected by a separate lead-in-wire.

2. An electron discharge tube as claimed in claim 1, wherein two support wires sealed in the envelope are secured to one electrode and are stepped outwardly away from the electrode system and extend beyond the active face of the said one electrode, the ends of the wires being sealed in insulating beads in each of which is also sealed one end of a wire the other end of which is secured to the second electrode, the insulating beads forming an insulating mechanical connection between the two sets of wires.

3. A diode comprising a cathode, cathode support and lead-in wires sealed in the envelope and secured to the cathode, an anode rigidly carried by the cathode supports by means including insulating beads of thermoplastic material which does not soften under the condi-

tions obtaining during normal operation of the diode, and a separate lead-in wire connected to the anode.

4. An electron discharge tube comprising an envelope, two adjacent electrodes and common supports for said electrodes sealed in the envelope, said supports directly carrying one of said electrodes and constituting the electrical connection thereto, insulating beads consisting of a glass which does not soften under the conditions obtaining during normal operation of the tube secured to said supports and to the other electrode for indirectly carrying said other electrode on said common support, and a separate lead-in wire constituting the electrical connection to said other electrode.

5. An electron discharge tube comprising an envelope, two adjacent electrodes substantially in contact and common supports for said electrodes sealed in the envelope, an insulating coating on one of said electrodes, said supports directly carrying one of said electrodes and constituting the electrical connection thereto, insulating beads of thermoplastic material which does not soften under the conditions obtaining during normal operation of the tube secured to said supports and to the other electrode for indirectly carrying said other electrode on said common supports, and a separate lead-in wire constituting the electrical connection to said other electrode.

6. An electron discharge tube comprising an envelope, a cathode electrode, another electrode adjacent to and substantially in contact with said cathode and common supports for said electrodes sealed in the envelope, an emissive oxide coating on said cathode, said supports directly carrying one of said electrodes and constituting the electrical connection thereto, insulating beads of thermoplastic material which does not soften under conditions obtaining during normal operation of the tube secured to said supports and to the other electrode for indirectly carrying said other electrode on said common supports, and a separate lead-in wire constituting the electrical connection to said other electrode.

7. In the method of manufacturing an electron discharge tube having an envelope, two adjacent electrodes substantially in contact and common supports for said electrodes sealed in the envelope the steps comprising, directly securing one of said electrodes to said supports, securing on said supports insulating beads of a thermoplastic material which does not soften under conditions obtaining during normal operation of the tube, fixedly securing the other of said electrodes to said insulating beads in a position adjacent to and substantially in contact with said directly secured electrode, sealing the said supports to one end of the envelope, and heating the said insulating beads to soften the same and permit movement of the electrodes relative to each other.

HOWARD JAMES LOUIS HERNE.
